CLAIM

The ornamental design for a combination waste bag and harness for dog, as shown and described.

DESCRIPTION

FIG. 1 is a front top perspective view of a combination waste bag and harness for dog showing my new design; FIG. 2 is a rear bottom perspective view thereof; FIG. 3 is a left side elevational view thereof; FIG. 4 is a right side elevational view thereof; FIG. 5 is a front elevational view thereof; FIG. 6 is a rear elevational view thereof; FIG. 7 is a top plan view thereof; and, FIG. 8 is a bottom plan view thereof.

The combination waste bag and harness for dog is shown with a symbolic break in its length. The appearance of any portion of the article between the breakaway lines forms no part of the claimed design.

The broken lines depict portions of the combination waste bag and harness that form no part of the claimed design.
